John Stephenson, of New York, N.Y.

DES. 1961

Letters Patent No. 1961-Dated June 14, 1864

Design for a Clog-hanger for R.R. Cars

The schedule referred to in these Letters Patent and making part of the same
is all whom it may concern:

Be it known that I, John Stephenson, in the City, County and State of New York, have invented or produced a new and original design for a Clog-hanger for Railroad Cars; and I do hereby declare that the following is a full, clear and exact description of the same, reference being had to the accompanying drawing, which is a part of this specification, said drawing being an elevation of my design.

This invention relates to a new and original design for a Clog-hanger used in the application of brakes to a city or horse-rail

A represents the fixed portion of the hanger which is composed of an upright tapering piece a, swelled at its centre so as to form a projecting ridge with a plane surface b, of equal width extending nearly the whole height of the piece a.

This fixed portion A also has a lateral arm or eye c, projecting from it, at its lower part, as shown in the drawing.

B is the link portion of the hanger which is fitted in an eye d, at the lower part of A. This link has its arms e, e, curved slightly so that their lower ends are rather nearer together than their upper ends, as shown in the drawing, and the lower ends of the arms e, e, have cylindrical hub-like projections f, f, through which a bolt G passes.

Having thus described my invention, I claim as new and desire to secure by Letters Patent:

the configuration of the parts as herein shown and described to form a new and original design for a Clog-hanger for Railroad cars.
